US00D597940S

(12) **United States Design Patent**
Navid

(10) **Patent No.:** **US D597,940 S**
(45) **Date of Patent:** **** Aug. 11, 2009**

(54) **VIDEO GAME CONTROLLER CHARGING APPARATUS**

(75) Inventor: **Amir Navid**, Sherman Oaks, CA (US)

(73) Assignee: **NYKO Technologies, Inc.**, Los Angeles, CA (US)

(**) Term: **14 Years**

(21) Appl. No.: **29/327,049**

(22) Filed: **Oct. 29, 2008**

(51) LOC (9) Cl. **13-02**

(52) U.S. Cl. **D13/108**

(58) Field of Classification Search **D13/107-110, D13/118-119, 184; D14/251, 253, 432, D14/434; 320/107-115**

See application file for complete search history.

(57) **CLAIM**

The ornamental design for video game controller charging apparatus, as shown and described.

DESCRIPTION

FIG. 1 is a front perspective view of a video game controller charging apparatus; and,

FIG. 2 is a right side view thereof, the left side being a mirror image of the right side.

The broken lines shown in the drawings are included for the purpose of illustrating environmental structure and form no part of the claimed design.
